UNITED STATES PATENT OFFICE.

JOSEPH A. MUDD, OF CHICAGO, ILLINOIS.

LOOSE-LEAF BINDER.

977,120.

Specification of Letters Patent. Patented Nov. 29, 1910.

Application filed April 19, 1909. Serial No. 490,868.

To all whom it may concern:

Be it known that I, JOSEPH A. MUDD, a citizen of the United States, residing at Chicago, in the county of Cook and State 5 of Illinois, have invented a new and useful Improvement in Loose-Leaf Binders, of which the following is a specification.

My invention relates particularly to loose leaf binders adapted for use as perpetual 10 ledgers; and my primary object is to provide a binder of the character indicated of improved construction and capable of wider expansion than binders of a similar type now on the market.

15 The invention is illustrated in its preferred embodiment in the accompanying drawings, in which—

Figure 1 represents a sectional view taken as indicated at line 1 of Fig. 4, and showing the binder in collapsed condition; Fig. 2, a similar section showing the binder in expanded condition; Fig. 3, a broken longitudinal section taken as indicated at line 3 of Fig. 1; Fig. 4, a broken sectional view 25 taken as indicated at line 4 of Fig. 2; Fig. 5, a broken sectional view taken as indicated at line 5 of Fig. 2; and Fig. 6, a broken sectional view taken as indicated at line 6 of Fig. 3.

30 In the construction illustrated, A represents a binder-back upon which is mounted a longitudinally disposed right-and-left threaded screw A¹; A², A², transversely slideable binding members mounted on the back 35 A and equipped with telescopic binding posts, or leaf supports, A³; A⁴, A⁴, nuts connected with the threaded rod, or screw, A¹ and joined, by links A⁵, to the slideable binder sections A²; and A⁶, cover sections 40 hinged, or flexibly connected, to the binder sections A².

The back section A of the binder frame preferably comprises a sheet-metal plate 1 having at its ends integrally formed guides 45 2; and a back piece 3, which may be of wood, detachably connected with the plate 1 by means of screws 4. The guides 2 are formed by bending the end portions of the plate 1 forwardly, or upwardly, (according 50 to the position of the binder) thereby providing an outer flange 5 formed by bending the metal back upon itself to provide an inner flange 6 separated from the flange 5 by a space 7. The extremities of the plate 55 are then extended inwardly to provide portions 8 which lie parallel with the body of

the plate 1, and the extreme end portions of the plate are then bent forwardly or upwardly and provided with perforations, thereby affording bearings 9 for the rod A¹. 60 Otherwise stated, the integral end-guides 2, the inwardly extending guide members 8, and the rod-bearings 9 may be provided by folding the end portions of the strip of sheet-metal 1 back parallel with the body 65 of the strip, and then bending the extremities or loop-ends of the folded parts forwardly or upwardly at right angles to the body of the plate to provide the guides 2 at right angles to the portions 8, and finally 70 bending the extremities of the inner plies of the material forwardly at right angles to the body of the plate to provide the bearings 9. As thus described, the bearings 9 are disposed parallel with the end-guides 2 75 with which the back-plate 1 is equipped. The rod A¹ is journaled in said bearings 9, and one end of the rod is provided with an angular extremity 10 adapted to receive a key, or wrench, 11. One of the end-guides 80 2 is provided with a perforation 12 through which the key may be inserted. The rear or loop side of the back piece 3 is shown covered with leather or other suitable covering material 13, whose edge portions are folded 85 over the inner surfaces of the piece 3. The covering material 13 may be secured by means of adhesive material. The inner flanges 6 of the guides 2 are provided at their lateral edges with notches 14, as shown 90 in Fig. 6.

Each slideable section A² of the binder-frame preferably comprises a light sheet-metal plate 15 having its end portions turned forwardly or upwardly at right 95 angles to the body of the plate to afford end flanges 16 adapted to move in the guides 2, and having its outer lateral edge portion turned up at right angles to the body of the plate to afford a flange 17; a heavier sheet-metal plate 18 rigidly secured to the flange 17, as by rivets 19; and an outer side-piece 20 which may be of wood. The wooden members 20 are shown connected with the metal plates 18 by means of screws 21 which 100 connect with nuts 22 which are embedded or countersunk in the outer surfaces of the members 20. The end-flanges 16 of the plates 15 are provided at their outer lateral edges with inturned lugs, or ears, 23 which 105 are secured, by rivets 24, to the end portions of the relatively thick plates 18. The plates

18 carry the telescopic sections of the binder-posts A³. The notches, or recesses, 14 of the inner members of the guides 2 receive the lugs, or ears, 23 when the binder is in the 5 completely collapsed condition, as will be understood from Fig. 6. The plates 18 have portions of the metal thereof severed and struck inwardly to afford lugs, or bearings, 25 with which the outer ends of the links A⁵ 10 are connected by pivots 26. The inner ends of the links A⁵ are connected with the nuts A⁴ by pivots 27. The wooden members 20 are incased in suitable covering material 28 whose edge portions are extended and 15 gummed or cemented to the cover-sections A⁶. The covering material 28 may be of leather, or other suitable flexible material, and said material may be employed to provide hinge connections 29 between the 20 binder-frame sections A² and the cover-sections A⁶. The nuts 22 are of angular form and are placed in the angular recesses, or 25 sockets, provided therefor in the outer surfaces of the members 20 before the covering material 28 is applied.

The rod A¹ may be rendered longitudinally immovable on the binder-frame back by providing a pin, or stud, 30 adjacent the bearing 9 at the key-receiving end of the 30 binder, and by allowing the opposite end of the rod to abut against the guide 2. Any other suitable expedient may be adopted for rendering the rod A¹ longitudinally immovable while permitting its rotation in the 35 bearings 9.

The inwardly extending portions 8 carried by the inner flanges 6 of the guides 2 are separated from the body of the plate 1 40 15 of the transversely slid able binder-sections A².

The operation will be readily understood from the foregoing description. When it is desired to open the binder, the rod A¹ may 45 be rotated in a direction to cause the nuts A⁴ to travel toward each other, thereby causing the links A⁵ to approach alinement with each other. The inward travel of the nuts may be limited by studs 32 with which 50 the rod is equipped. In the collapsing operation, the rod is rotated in the opposite direction, thereby causing the nuts to travel away from each other and drawing the binder sections A² together. In the 55 completely collapsed condition of the binder, the lateral edges of the guides 2 abut against the side members 20, as shown in Fig. 1, and the ears, or lugs, 23 are received in the slots, or recesses, 14 with which the inner members of said guides are provided. It will be noted from Figs. 2 and 6 that the side plates 18 of the binder sections A² are somewhat shorter than the back plate 1, so that the guides 2 embrace the ends of the plates 18 60 75 when the binder is in the completely col-

lapsed condition. The back piece 3 and the side pieces 20 preferably project at their ends somewhat beyond the guides 2 and flanges 16.

It will be understood that if a flat-back 70 binder is desired, instead of a round or curved back binder, the back piece may be dispensed with; and, if desired, the side pieces 20 may be omitted and the cover sections suitably connected with the plates 18, 75 in which case the binder-frame may be nickel-plated.

The construction described is simple, strong and durable and may be manufactured at moderate cost. Moreover, the 80 binder possesses the utmost smoothness and certainty of operation, and may be expanded to practically twice the capacity which it possesses in the collapsed condition. The slotted perforate leaves may be inserted and 85 connected with the posts A³ in the usual manner.

The foregoing detailed description has been given for clearness of understanding only. Hence, no undue limitation should be 90 understood therefrom, but the appended claims should be construed as broadly as permissible in view of the prior art.

What I regard as new, and desire to secure by Letters Patent, is— 95

1. In a binder of the character set forth, the combination of a back section comprising a sheet-metal plate having its end portions folded upon the body of the plate and the extremities of the folded portions bent 100 forwardly to afford end-guides, the inner plies of the material being separated from the outer plies by spaces, slid able sections mounted on said back and provided with flanges received by said guides, and mechanism connecting the back section and said 105 slid able sections.

2. In a binder of the character set forth, the combination of a back section comprising a sheet-metal member having its extremities folded back to lie parallel with the body of the plate and the loop ends of the plies thus formed bent forwardly at right angles to the body of the plate to afford end-guides, the portions of the inner plies 115 lying parallel with the body of the plate affording back guide-members and the extremities of the inner plies bent at right angles to the body of the plate and provided with perforations affording rod-bearings, 120 a right-and-left threaded rod journaled in said rod-bearings, post-equipped binder sections having flanges engaging said guides, nuts on said rod, and links connecting said second-named binder sections with said nuts. 125

3. In a binder of the character set forth, the combination of a back section equipped with end-guides and back guides, a pair of transversely slid able sheet-metal sections having flanges received in said guides and 130

- post-carrying flanges at right angles thereto, a rod journaled on said back and equipped with nuts, links connecting said nuts with said pair of transversely slidable sections, 5 a pair of side pieces flanking said post-carrying flanges of said slidable sections, said side pieces having nut-receiving sockets in their outer surfaces, nuts in said sockets, screws extending through the metal post-carrying flanges and connected with said nuts, a pair of cover sections, and binding material covering said side pieces and connected with said cover sections and affording flexible connections between the cover sections 10 and the transversely slidable sections of the binder frame.
4. In a binder of the character set forth, the combination of a sheet-metal back section having forwardly extending end-guides 15 formed integrally therewith, said end-guides comprising inner and outer plies of metal, a pair of transversely slidable sheet-metal binder sections, each comprising a sheet-metal plate having its extremities extending 20 forwardly at right angles to the body of the plate and having at its outer lateral edge a flange extending forwardly at right angles to the body of the plate, said end portions received by said guides of said back section 25 and having inwardly turned ears, the inner plies of said end-guides having recesses to accommodate said ears in the collapsed condition of the binder, and a relatively short and thick sheet-metal side plate 30 secured to said forwardly turned lateral flange and to said ears, binding-posts carried by said relatively thick side plates, a right-and-left threaded rod journaled on said back section 35 and equipped with nuts, and links connecting said nuts to said relatively thick plates.
- said back section and equipped with nuts, and links connecting said nuts to said transversely slidable binder-sections. 40
5. In a binder of the character set forth, the combination of a sheet-metal back section having forwardly extending double-ply end-guides with the plies thereof separated 45 to afford guide spaces, the inner plies of said end-guides having their lateral edges provided with recesses, a separately formed back piece of wood, or the like, secured to the body of said sheet-metal back section and 50 having its edges projecting beyond the edges of the sheet-metal back piece and beyond said end-guides, a pair of transversely slidable sheet-metal binder sections, each comprising a sheet-metal plate having its extremities bent forwardly and forming guide flanges received in said guides of said back section, the outer lateral edges of said end flanges having inturned ears, and relatively short and thick sheet-metal side plates 55 secured to said ears and adapted to fit between said end-guides in the collapsed condition of the binder, binder-posts carried by said last-named plates, separately formed side pieces of wood, or the like, secured to 60 said last-named plates and having their extremities projecting beyond the ends of said plates, cover sections flexibly connected with said last-named side pieces, a right-and-left threaded rod journaled on said back section 65 and equipped with nuts, and links connecting said nuts to said relatively thick plates. 70
